SEWING MACHINE

Clarence S. Best, Belvidere, Ill., assignor to
National Sewing Machine Company, Belvidere,
Ill., a corporation of Illinois

Application June 18, 1945, Serial No. 600,131

7 Claims. (Cl. 112—236)

1

This invention relates to improvements in sewing machines, and particularly to presser foot controlling means.

In conventional sewing machines, the presser bar which carries the presser foot is provided with lever actuated means for raising the bar and lifting the foot to inoperative position, out of contact with the work, and for lowering the bar and moving the foot to operative position in contact with the work on the feed point. For ordinary sewing, this provision of means for moving the presser foot and retaining it in one of two extreme positions is adequate.

However, for certain types of work, particularly mending and darning, it is desirable to move the work manually back and forth between the feed point and the presser foot, and under such conditions the presser foot must not be under such tension as to exert undue pressure on the work and interfere with the operator's efforts to move the work back and forth. On the other hand, it is not possible to perform the work properly when the presser foot is in its conventional raised position.

Heretofore operators have attempted to overcome the lack of proper control means by altering the tension of the tension spring associated with the presser bar, in order to gain the desired pressure on the presser foot. Such alteration of the tension and the restoring of the proper tension for ordinary sewing has proven very unsatisfactory as well as time and effort consuming. Frequently the result has been failure to restore the proper tension and consequent difficulty in performing subsequent work.

The main object of my invention is to provide, in addition to the conventional lever actuated means for moving the presser bar and foot to operative and inoperative positions, auxiliary control means whereby the presser foot may be positioned so as to permit manipulation of the work by the operator without interfering with the adjustment of the presser bar tension.

In the drawings:

Fig. 1 is an elevational view of a sewing machine head embodying my invention.

Fig. 2 is a perspective view of the end portion of the sewing head of the machine.

Fig. 3 is a transverse, vertical sectional view through the sewing head, showing in elevation the presser bar and control mechanism therefor.

Fig. 4 is a sectional view of a detail of construction, taken in the plane of the line 4—4 of Fig. 3.

In that embodiment of the invention shown

2

in the drawings, conventional parts of the sewing machine include the bed plate 10, upright standard 11, overhanging arm 12, sewing head 13, fly wheel 14, presser bar 15 and presser foot 16. Part of the needle bar is indicated at 17 in Fig. 3.

The presser bar 15 is mounted for vertical reciprocatory movement in the sewing head 13, in a bearing 18, and above the bearing is the usual presser bar tension releasing member or cage 19 and compressible spring 20. The presser bar has a set screw 21 projecting from its side and through the slot 22 of the cage 19 for controlling the travel of the presser bar under tension of the spring 20 as is well understood in the art.

The means employed for raising and lowering the presser foot 16 comprises a lever 23 integral with a cam head 24 pivotally mounted on a pivot screw 25 fastened to a fixed portion of the head 13 in such position that the cam engages the lower plate portion of the cage 19. In Fig. 3, the dotted lines show the lowered position of the lever 23 and cam head 24. In this position the presser foot 16 engages the work. The full line position of the lever 23 and cam head 24 show the lever in the act of being raised. However, in this view, the cam 24 has not reached the height of its lifting action on the cage 19 and presser bar 15, for the purpose of this figure is to illustrate the operation of the auxiliary control cam 26. The cam 26 has an actuating lever 27 and is pivotally mounted by the pin 28 on the lower part of the head casting, in such position that the presser bar 15 can be engaged and disengaged by the cam 26.

The operation of the presser bar controlling means is as follows: for ordinary sewing, the operator uses the control lever 23, raising it to the utmost extent when it is desired to hold the presser foot in inoperative position, out of contact with the work, and lowering it to its other extreme position, in contact with the work, for the sewing operation. When the operator desires to mend or darn, and requires the presser foot to be raised to an intermediate position, permitting manual control of the work, while maintaining controlled pressure on the work, the auxiliary control lever 27 is utilized in combination with the regular control means for the presser bar. First the operator uses the lever 23 to raise the presser foot 16 slightly above its lowermost position, and while holding the lever 23 the operator raises the lever 27 to bring the high side of the cam 26 into frictional engagement with the presser bar 15 and thereby hold the presser bar in se-

lected position. When it is desired to release the holding action of the auxiliary control cam 26, the operator raises the lever 23 slightly and thereby raises the presser bar 15, which action breaks the locking action of the cam 26 by rotating it in the direction indicated by the small arrow on the cam 26 in Fig. 3. Thereafter, the lever 23 may be employed to raise or lower the presser bar as heretofore explained, and the auxiliary cam 26 remains inoperative until it is again actuated by its lever 27.

Changes may be made in details of construction and form of the parts without departing from the scope of my invention as set forth in the appended claims.

I claim:

1. A sewing machine comprising a sewing head, a vertically reciprocable presser bar and foot mounted in the head, manually actuated lifter means for moving said presser bar and foot to a predetermined raised position and to a work-engaging position, and lever operated retaining means adapted to bear on the presser bar and rigidly lock it against downward movement after having been moved to an intermediate position by said lifter means.

2. A sewing machine comprising a sewing head, a vertically reciprocable presser bar and foot mounted in the head, manually actuated lifter means for moving said presser bar and foot to a predetermined raised position and to a work-engaging position, and manually operable retaining means adapted to engage the presser bar and rigidly lock it against downward movement after having been moved to an intermediate position by said lifter means, said retaining means comprising a cam pivotally mounted on the sewing head adjacent the presser bar and a lever rigidly connected to the cam.

3. A sewing machine comprising a sewing head, a vertically reciprocable presser bar and foot mounted in the head, tension means on the presser bar, a lifter cam pivotally mounted on the sewing head in position to actuate the tension means and presser bar, a lever for actuating the lifter cam and thereby moving said presser bar and foot to a predetermined raised position and to a work-engaging position, and lever operated retaining means adapted to bear on the presser bar and rigidly lock it against downward movement after having been moved to an intermediate position by said lifter cam.

4. A sewing machine comprising a sewing head, a vertically reciprocable presser bar and foot mounted in the head, tension means on the presser bar, a lifter cam pivotally mounted on the sewing head in position to actuate the tension means and presser bar, a lever for actuating the lifter cam and thereby moving said presser bar and foot to a predetermined raised position and to a work-engaging position, and manually operable retaining means adapted to engage the presser bar and retain it in an intermediate position

after having been moved to such intermediate position by said lifter cam, said retaining means comprising a cam pivotally mounted on the sewing head adjacent the presser bar and a lever rigidly connected to the cam.

5. A sewing machine comprising a sewing head, a vertically reciprocable presser bar and foot mounted in the head, manually actuated lifter means for moving said presser bar and foot to a predetermined raised position and to a work-engaging position, and lever operated retaining means adapted to bear on the presser bar and rigidly lock it against downward movement after having been moved to an intermediate position by said lifter means, said retaining means being releasable from the presser bar by actuating the lifter means to slightly raise the presser bar above its locked position.

6. A sewing machine comprising a sewing head, a vertically reciprocable presser bar and foot mounted in the head, tension means on the presser bar, a lifter cam pivotally mounted on the sewing head in position to actuate the tension means and presser bar, a lever for actuating the lifter cam and thereby moving said presser bar and foot to a predetermined raised position and to a work-engaging position, and lever operated retaining means adapted to bear on the presser bar and rigidly lock it against downward movement after having been moved to an intermediate position by said lifter cam, said retaining means being releasable from the presser bar by actuating the lifter cam to slightly raise the presser bar above its locked position.

7. A sewing machine comprising a sewing head, a vertically reciprocable presser bar and foot mounted in the head, manually actuated lifter means for moving said presser bar and foot to a predetermined raised position and to a work-

engaging position, and manually operable retaining means adapted to engage the presser bar and retain it in an intermediate position after having been moved to such intermediate position by said lifter means, said retaining means comprising a cam pivotally mounted on the sewing head adjacent the presser bar and a lever rigidly connected to the cam, said retaining cam being releasable from the presser bar by actuating the lifter means to slightly raise the presser bar above its retained position.
